MULTIPLYING MACHINE

James M. Cunningham, Endicott, N. Y., assignor
to International Business Machines Corporation,
New York, N. Y., a corporation of New York

Application October 24, 1936, Serial No. 107,313

6 Claims. (Cl. 235—61.10)

This invention relates to multiplying machines and more particularly to multiplying machines of the type disclosed in my Patent No. 1,933,714, granted November 7, 1933.

5 In such patent there is disclosed mechanism for entering two factors from a record card and multiplying the factors to obtain their product after which the product is punched back in the card in the form of coded perforations.

10 The object of the present invention is to provide a novel controlling mechanism for the punching devices whereby when the product is in the form of a whole number and a decimal the machine automatically punches the whole number only.

15 A further object is to provide a novel control of the punching devices to punch a "1" when the computed product is wholly decimal.

20 Various other objects and advantages of the invention will be obvious from the following particular description of one form of mechanism embodying the invention or from an inspection of the accompanying drawings; and the invention also constitutes certain new and useful features 25 of construction and combination of parts hereinafter set forth and claimed.

In the drawings:

Fig. 1 is a diagram of the essential circuits of the device.

30 Fig. 2 is a view showing the essential elements of one order of an accumulator.

Fig. 3 represents a problem handled as by the device.

35 In Fig. 1 there is shown so much only of the circuit diagram of the machine as is necessary for an understanding of the invention. The light lines indicate the wiring found in the machine of my prior patent and the heavier lines represent the devices and circuits that have been added to carry out the objects of the present invention. In describing the old mechanism, the reference characters employed in the patent will be utilized so that ready reference may be made thereto for a more complete understanding of 40 the prior art to which the present improvements have been applied.

45 In the center of Fig. 1 are columns of circles with vertical rectangles adjacent thereto. This is a diagrammatic representation of the so-called "readout" device LHRO of the accumulator known as the LH accumulator, which accumulator contains the product computed during the operation of the machine. The product is represented by the differential displacement of sets 50 of contact brushes 10, 10a of which there is one

set for each denominational order of the accumulator.

The brush 10 is adapted to bridge and form an electrical connection between one of the segments 11 and a common conductor 12 while the brush 10a similarly connects one of the segments 13 with a common conductor 14. Thus, if the product computed were the number 8768521, the brushes 10, 10a would be displaced as indicated by dotted lines in Fig. 1.

10 The segments 11 are connected to wires 15 extending to segments 16 of emitter 154 whose rotating brush emits impulses to lines 15 in succession in the order 9, 8, 7, 6, etc. to complete circuits through the positioned brushes 10, 10a 15 and these timed impulses will energize magnets 190SP of a so-called summary products accumulator which receives all the separate products to totalize the same.

20 The essential elements of this SP accumulator are shown in Fig. 2 in which the constantly running shaft 17 has keyed thereto for rotation therewith a clutch element 18. This element is slidably along the shaft and is provided with a circular groove into which the short end of a 25 lever 19 extends. The lever 19 carries a block 20 which is engaged by armature latch 21 to hold the lever in the position shown, against the pressure of blade 22 of a pair of normally open contacts 23. These contacts have been added to the 30 usual accumulator structure for the purposes of the present invention.

Upon energization of magnet 190SP, armature latch 21 will be rocked about its pivot 24 to release lever 19 which will thereupon turn counter-clockwise to engage clutch element 18 with teeth 25 integral with gear 26 so that the latter will be turned. Gear 26 meshes with gear 27 carried by index wheel 28 which displays the value entered. Near the end of the cycle a bar 29 is 40 shifted to the right and a finger 30 thereon will engage the extremity of lever 19 to rock it back to its latched position. The operation of this bar 29 is synchronized with the operation of emitter 154 to shift to the right one step after 45 the "1" segment 16 of the emitter has been contacted. Thus, if an impulse were sent through the "1" segment 16 to energize magnet 190SP, the clutch would be engaged for one step and then positively disengaged with the result that wheel 50 28 would have been moved one step. If the impulse had been transmitted through the "2" segment 16 the clutch would have been engaged for two steps before being knocked out and wheel 55 28 would have advanced two steps and so on.

The value entered into any order of the SP accumulator is thus dependent upon the time at which the clutch is tripped prior to its point of knock-out. This is the manner of operation 5 of the well known Hollerith accumulator which includes the usual tens carry mechanism which need not be described herein.

The circuits involved in operating the SP accumulator will be understood by the tracing of a 10 representative circuit through the right hand order of the LHRO readout, for example. When contacts RHD and LHA have closed during prior operations of the machine, a circuit is traceable when the emitter brush contacts its "1" segment 16 as follows: from AC source 52, line 763, contacts RHD, LHA, emitter 154, "1" segment 16, "1" line 15, "1" segment 11, brush 10 (in dotted position), conductor 12, and right hand magnet 790SP to ground through the usual plug connection shown. It will be appreciated that as the 20 emitter 154 operates the amounts in the several orders of the LHRO will control similar circuits concurrently so that all orders of the SP accumulator that are to receive "9's" complete circuits at the "9" time; all that are to receive "8's" at the "8" time and so on.

Following this cycle of operations, the LHRO controls the energization of the punch selecting 30 magnets 792 column by column from left to right or highest to lowest order. At the commencement of punching operations, column selecting brush 614 is in position bridging conductor 613 and segment 612 corresponding to the column of the card that is to receive the highest order digit.

Supply of current for the punch selector common supply line 783 is provided at the proper time in the operation of the machine in the following manner. Upon closure of contacts LHC in the well known manner, closure of cam contacts CC-3 at the "T" time in the cycle will cause current to flow from DC supply 52, line 762, contacts LHC, CC-3, wire 794 to relay coil B and line 761 to source DC. Energization of B closes its contacts B-1 and this provides a supply of current through the circuit to line 793 including contacts 809, 772a and switch 806. From 793 the circuit continues to conductor 613, brush 614 (in dotted position), segment 612, plug socket 30, plug contacts 31, to socket 32, conductor 14, brush 10a, segment 13, wire 33, a magnet 792 to line 761. The magnet 792 energized will be that corresponding to the segment 13 at which brush 10a is set.

Energization of any magnet 792 will cause closure of contacts 805 to energize punch operating magnet 804 which causes the appropriate position in the selected card column to be punched and also escapes the column selecting brush 614 to the next segment 612 to the right. Thereupon the circuit just traced is again completed in accordance with the setting of the next brush 10a and so on.

The operation of the machine as thus far outlined is the same as in my prior patent and in 45 commercial machines with the exception of the closure of the added contacts 23. A further difference resides in the fact that the punching operations follow after the operation of transferring the setting of the LHRO device to the SP accumulator whereas in the patent these operations are concurrent. This change is brought about by re-timing cam contacts CC-3 which, as pointed out hereinabove, close at "0" while in the patent they close earlier in the cycle i. e. near the beginning, so that with contacts RHD, LHA

and LHC closed, emitter 154 sends impulses to the magnets 790SP through LHRO at the same time that CC-3 energizes relay B. In the present instance CC-3 is open during the period that the brush of emitter 154 wipes segments 16 and 5 closes at "0" or just after the "1" segment 16 has been traversed by the brush. Thus the entries into magnets 790SP are made and relay Z and its contacts Z-2 and Z-3 adjusted before 10 closing its contacts B-1 which provide a return circuit through contacts LHC. Contacts LHC are closed by magnet 784LH of the patent and opened when accumulator LH is reset which in turn takes place when the card has reached the so-called 15 "last column" position.

The SP accumulator has eight denominational orders in each of which there is a pair of contacts 23, numbered 1 to 8 on Fig. 1, and when an entry is made in any order, the corresponding 20 contacts 23 close. If a switch 34 is closed, a circuit is completed from line 762, switch 34, contacts 23, a relay Z to line 761. Relay Z will close its contacts Z-1 which establishes a holding circuit through contacts B-1 and LHC. Thus 25 relays Z and B are held for the same period. Relay Z also controls pairs of contacts Z-2 and Z-3 at the top of Fig. 1 and if an entry is made into any order of the SP accumulator whose switch 34 is closed, the contacts Z-2 will be 30 closed during punching operations and contacts Z-3 will be open.

Let us assume now that the product in the LH accumulator is a whole number and a decimal with the whole number part entered in the 8, 7, 35 and 6 positions and the decimal part in the remaining positions. If only the three highest order switches 34 are closed, relay Z will be responsive to only entries in these three orders and if any thereof contains a significant digit, relay Z 40 will be energized when the product is transferred from the LH to the SP accumulator.

If only the whole part of the product is to be punched, only three segments 612 are plug connected, the 8 and 7 positions by means of connections 34 and the sixth position by connections 35 and 36 as shown. An additional connection 37 is also made between sockets 38 and 39.

With this arrangement, if accumulator LH contains the product 87.68521 (see Fig. 3), this 50 amount will be entered into the corresponding orders of the SP accumulator and in so doing, contacts 23 in the 7 and 6 positions will be closed, relay Z will be energized and its contacts Z-2 and Z-3 shifted. During the ensuing punching 55 operations a circuit will be completed through the zero position of the 8 order of the LH accumulator to energize the "0" magnet 792 and a zero will be punched. In a similar manner, an 8 will be punched under control of a circuit through 60 the seventh order. For the sixth order, the punch selecting circuit will be traced from wire 783, common 613, brush 614, segment 612, socket 30, connection 35, contacts Z-2 (now closed), connection 36, common 14, brush 10, segment 7, wire 65 33, 7 magnet 792 to line 761. The amount punched in the card is thus 087 as indicated in Fig. 3.

Where the product is wholly decimal as, for example, the value .64120 indicated in Fig. 3, none 70 of the contacts 23 whose switches 34 are closed, will be operated and consequently relay Z will not be energized prior to the punching operations. When such operations take place, circuits will be completed to energize the zero magnet 792 75

under control of the brush setting in the 8 and 7 positions of the LH accumulator in the normal manner. When brush 614 reaches the third segment 612, however, a circuit is completed 5 which may be traced as follows: from wire 793, common 613, brush 614, segment 612, socket 30, connection 35, contacts Z-3, wire 40, socket 38, connection 37, socket 39, "1" magnet 792 to line 161. The number punched will thus be 001 as 10 indicated in Fig. 3.

With the arrangement described, therefore, whenever the product contains significant digits in certain selected positions, the punching will be in accordance with the true amount and when 15 no significant digits are present in such positions a "1" will be punched in a selected columnar position of the record card.

While there has been shown and described and pointed out the fundamental novel features of 20 the invention as applied to a single modification, it will be understood that various omissions and substitutions and changes in the form and details of the device illustrated and in its operation may be made by those skilled in the art without de- 25 parting from the spirit of the invention. It is the intention therefore to be limited only as indicated by the scope of the following claims.

What is claimed is as follows:

1. In a machine of the class described, a plurality of denominational ordered accumulator elements settable to represent an amount, an accumulator, means for transferring said amount from said plurality of elements to said accumulator, means controlled by predetermined elements of said transferring means for ascertaining whether the amount transferred contains significant digits in corresponding predetermined orders, punch selecting devices, normally ineffective means for causing one of said accumulator 35 elements to control the operation of said punch selecting devices, and means controlled by said ascertaining means for rendering said last named means effective when any one of said certain orders contains a significant digit.
2. In a machine of the class described, a plurality of denominational ordered accumulator elements settable to represent an amount, means controlled by said elements for ascertaining whether the amount represented contains significant digits in predetermined orders, punch se- 45

lecting devices, normally ineffective means for causing one of said accumulator elements to control the operation of said punch selecting devices, and means controlled by said ascertaining means for rendering said last named means effective 5 when any one of said predetermined orders contains a significant digit.

3. In a machine of the class described, a read-out device having a plurality of denominational ordered elements, each element settable to represent a digit of a number, a plurality of magnets one for each digit of a rotation, means for connecting each element in turn for control of said magnets in accordance with the digital setting of the connected element, means controlled by said elements for ascertaining whether all said elements are set to represent zero, and means controlled thereby for preventing control of any of said magnets by a predetermined one of said elements when all are set at zero. 20

4. The invention set forth in claim 3 in which means is provided and controlled by said ascertaining means for energizing the magnet corresponding to the digit "1" when the element whose control is prevented is connected for control. 25

5. The invention set forth in claim 2 in which normally effective means is provided for controlling the operation of one of said punch selecting devices and further means is provided and controlled by said ascertaining means for rendering said normally effective means ineffective when any one of said certain orders contains a significant digit. 30

6. In a machine of the class described an accumulator element settable to represent any digit, a plurality of magnets one for each digit of a rotation, a circuit connection normally effective to energize a predetermined one of said magnets, a second circuit connection normally ineffective and controlled by said accumulator element for energizing the magnet corresponding to the digital value represented by the setting of said accumulator element, means controlled by said element for ascertaining whether said element is set to represent zero or a significant digit and means controlled thereby when the element is set to represent a significant digit for rendering said normally effective circuit connection ineffective and said second circuit connection effective. 45

JAMES M. CUNNINGHAM. 50

CERTIFICATE OF CORRECTION.

Patent No. 2,217,158.

October 8, 1940.

JAMES M. CUNNINGHAM.

It is hereby certified that error appears in the printed specification of the above numbered patent requiring correction as follows: Page 3, second column, lines 12 and 37, claims 3 and 6 respectively, for the word "rotation" read --notation--; and that the said Letters Patent should be read with this correction therein that the same may conform to the record of the case in the Patent Office.

Signed and sealed this 12th day of November, A. D. 1940.

(Seal)

Henry Van Arsdale,
Acting Commissioner of Patents.
